DISPLAY STAND

Erich O. Steudel, Chicago, Ill.

Application July 2, 1932. Serial No. 620,604

6 Claims. (Cl. 211—73)

The invention relates to display devices and particularly to that type which is made of paper or some other flexible material which may be stamped or otherwise cut to produce a blank capable of being fashioned to form.

It is an object of the invention to produce the device of a strip of material which is formed in a manner so that when the ends of the strip are brought together in locked relation with each other and an article arranged thereon, the article will be displayed at an inclination to the horizontal.

It is a further object of the invention to provide the device with means whereby the circumference may be varied to compensate for and display articles of various dimensions.

It is another object of the invention to provide a locking means having means associated therewith which will assist to maintain the ends of the blank in locked relation with each other.

The invention has these and other objects, all of which will be explained and more readily understood when read in conjunction with the accompanying drawing which illustrates one embodiment of which the invention is susceptible, it being manifest that changes and modifications may be resorted to without departing from the spirit of the appended claims forming a part hereof.

In the drawing, Fig. 1 is a plan view of a blank having means formed therein for locking the opposite ends thereof together and having means whereby, when the ends of the blank are locked together, a device is formed capable of supporting an article at an inclination to the horizontal;

Fig. 2 is a central section through a device formed of the blank shown in Fig. 1;

Fig. 3 is a view showing in detail the locking means employed in the structure;

Fig. 4 is a section taken on line 4—4 of Fig. 3, and

Fig. 5 is a sectional view similar to Fig. 2 showing a modified construction which may be employed.

As before stated, the device is designed to be produced from a blank which is stamped or otherwise formed so that the several advantages of the invention may be accomplished. To this end, a strip of material 10 is employed, the strip being preferably made of cardboard or some other material which is capable of being bent so as to allow the opposite ends such as 11 and 12 of the strip to be brought together into locked relation and thus provide an annular member

capable of being arranged in a vertical position and support an article arranged thereon. One edge 13 of the strip or blank is preferably straight whereas the other edge such as 14 is inclined. In the structure illustrated in Fig. 1, the opposite ends of the strip are provided with locking means 11 and 12, the edge 14 being inclined from said ends to the center of length of the strip to thus produce the inclined edge 14 upon which a pie or cake plate may be arranged. It is evident that when the opposite ends 11 and 12 of the strip are brought together and connected with each other an annular element is formed, one edge of which, such as that designated 14 is disposed at an angle to the horizontal and thus, is capable of displaying an article such as a pie or cake at an inclination to the horizontal.

The opposite ends 11 and 12 are each provided with an element of a locking means respectively designated 15 and 16 and in addition thereto is provided with a plurality of slots such as 17 and 18. The locking elements such as 15 and 16 preferably take the shape of a tongue, one of which such as the tongue 16 being adapted to cooperate with the slots 17 in the end 11 whereas the tongue 15 is adapted to cooperate with the slots 18 in the end 12, it being understood that the tongues 15 and 16 are capable of being respectively introduced to any one of the several slots 17 and 18 to thereby separably lock the ends 11 and 12 in connected relation with each other and thus vary the diameter of the device and form an annular member.

Each of the ends 11 and 12 is provided with elements such as those designated 19 and 20 which operate upon the respective tongues 15 and 16 to maintain the tongues in the slots respectively designated 17 and 18, as shown in Fig. 4, and retain the ends in locked relation.

Another embodiment of the invention contemplates providing an edge such as 14 of the device with a plurality of either scored or slotted portions 23 so as to produce the elements 24 which may be bent laterally relatively to the strip and provide supports for the pie or cake plate and in addition provide means capable of holding the plate against displacement relatively to the display device.

From the foregoing description of the structure, it is evident that when the opposite ends 11 and 12 are brought together and connected with each other, that an annular element is formed, one edge of which such as 14 is disposed at an angle to the horizontal which will thus support a pie or cake plate at an inclination and thereby dis-

play a commodity contained on said plate to better advantage. It is understood that the strip 10 is provided with a plurality of slits such as 17 and 18 to provide means for varying the diameter of the device. It is further understood that in one embodiment of the invention, the dished portion such as that designated 21 of the plate, is adapted to be located within the circumference of the display member with the annular flange 22 of the plate supported by the inclined edge 14 to thus prevent displacement of the plate.

It is also evident from the foregoing that provision is made through the medium of the elements 24 for holding the plate against accidental displacement relatively to the device, which also act to support the plate in proper relation to the opening formed by the annular member.

Having thus described the invention, what I claim as new and desire to cover by Letters Patent is:

1. A strip of material forming a display stand, said strip having an element of locking means provided at the opposite ends thereof and having a plurality of slits provided at the opposite ends, one end being engageable with any slit in the opposite end to provide an annular member, one edge of said strip between said ends being inclined from said ends to the center of length of said strip, said strip providing an annular member which is of a lesser height at one portion than at another portion thereof to thereby support and display an article at an angle to the horizontal.

2. A strip of material providing a display stand, said strip having an element of locking means provided at the opposite ends thereof and having a plurality of slits provided at the opposite ends, one end being engageable to cooperate with any slit in the opposite end to provide an annular member, said locking means including means assisting to maintain same in locked relation, one edge of said strip between said ends being inclined from said ends to the center of length of said strip, said strip providing an annular member which is of a lesser height at one portion than at another portion thereof to thereby support and display a substantially flat article at an angle to the horizontal.

3. A display device comprised of a strip of flexible material having means provided at the opposite ends thereof which cooperate with each other to lock said ends together and form an endless member adapted to be supported upon one

edge and support an article arranged upon the other edge, one edge of said strip being formed to provide an edge which is inclined to the horizontal to thereby support said article at an incline to the horizontal, said edge providing a support for said article having adjustable means bendable laterally with respect to said edge.

4. A strip of material forming a display stand, said strip having an element of locking means provided at the opposite ends thereof and having a plurality of slits provided at the opposite ends, each end being engageable with any slit in the opposite end to lock the ends of the strip and thus provide an annular member, one edge of said strip between said ends being inclined from certain points from said ends to the center of length of said strip, said strip providing an annular member which is of a lesser height at one portion than at another portion thereof to thereby support and display an article at an angle to the horizontal.

5. A strip of material providing a display stand, said strip having an element of locking means provided at the opposite ends thereof and having a plurality of slits provided at the opposite ends, each end being engageable to cooperate with any slit in the opposite end to provide an annular member, said locking means including means assisting to maintain same in locked relation, one edge of said strip between said ends being inclined for a distance from certain points from said ends to the center of length of said strip, said strip providing an annular member which is of a lesser height at one portion than at another portion thereof to thereby support and display an article at an angle to the horizontal, the inclined portion of said edge having adjustable means bendable laterally with respect to said edge.

6. A display device comprised of a strip of flexible material having means provided at the opposite ends thereof which cooperate with each other to lock said ends together and form an endless member adapted to be supported upon one edge and support an article arranged upon the other edge, one edge of said strip being formed to provide an edge portion which is inclined to the horizontal a certain distance to thereby support said article at an incline to the horizontal, the inclined portion of said edge providing a support for said article having adjustable means bendable laterally with respect to said edge.
